HEINRICH ALBERT WALTER DRECHSLER, OF MÄNNEDORF, SWITZERLAND.

INTERNAL-COMBUSTION ENGINE.

No. 864,086.

Specification of Letters Patent.

Patented Aug. 20, 1907.

Application filed January 30, 1907. Serial No. 354,811.

To all whom it may concern:

Be it known that I, HEINRICH ALBERT WALTER DRECHSLER, a citizen of the Republic of Switzerland, and a resident of Männedorf, Switzerland, have invented a new and Improved Internal-Combustion Engine, of which the following is a full, clear, and exact description.

This invention relates to certain improvements in internal-combustion engines, and more particularly 10 that type known as the two-cycle engine.

The object of the invention is to provide certain improvements in the means for compressing the explosive charge and delivering it to the cylinder.

A further object of the invention is to provide means 15 whereby the time of admission of the gas to the cylinder may be controlled, rather than the time of ignition, and thus permitting the employment of a piece of platinum or other catalytic substance, as the igniter.

A further object of the invention is to provide means 20 whereby the exhaust gas from the chamber may escape through the piston rod, after the main exhaust-port has been closed.

Reference is to be had to the accompanying drawings, forming a part of this specification, in which similar characters of reference indicate corresponding parts 25 in all the figures.

Figure 1 is a longitudinal section through my improved engine; Fig. 2 is a detail showing the inlet controller; Fig. 3 is a detail showing the wrist-pin in the 30 exhaust position; Fig. 4 is a side elevation of the piston rod, and means for connecting the same to the wrist-pin; Fig. 5 is a section on the line 5—5 of Fig. 1; and Fig. 6 is a section on the line 6—6 of Fig. 1.

In the specific form of my improved engine which I 35 have illustrated in the drawings, I employ the customary cylinder 1 having heads 2 and 3 secured thereto, and spaces provided within the walls of the cylinder and cylinder heads whereby water may be circulated to keep the cylinder at the desired temperature. The 40 piston 4 is cylindrical in shape and provided with an interior space 5, having an inlet port 6 at one end and an exhaust port 7 extending through one side thereof. The inlet port 6 is in the end of the piston opposite to the 45 explosion chamber of the cylinder, and is controlled by a flap valve 8 whereby gas may be admitted to the hollow space of the piston through the port 6 but cannot escape save through the exhaust port 7. The piston is provided with a piston rod 9 extending entirely through the piston and having a flange 10 preventing the movement of the piston in one direction 50 along the piston rod, and a nut 11 at opposite side of the piston for holding it in place. The piston rod is hollow and the passage 12 communicates with explosion chamber of the cylinder and is controlled at the outer

end by the wrist pin 13. This pin is carried by a 55 connecting rod 14 and has an axial passage extending therethrough and communicating with the atmosphere at both ends. A radial passage 16 leads from the axial passage 15 to the circumference of the wrist-pin within the piston rod, and as the angle of the connecting rod 60 14 and the piston rod 9 changes, the radial passage 16 is alternately brought into and out of communication with the passage 12 of the piston rod.

The piston rod extends through the cylinder head 2 and is provided with any suitable form of packing and 65 packing box 17. Adjacent this packing box is the inlet pipe 18 communicating with the carburetor or mixing chamber and serving to deliver the explosive charge into the cylinder at the rear of the piston. Any suitable form of valve 19 may be provided for controlling 70 the admission of the gas from the pipe 18.

Within the cylinder wall, at the end opposite to the inlet pipe 18, is arranged a plate 20 dovetailed to prevent the lateral displacement thereof, and provided with a rod 21 extending out through a packing in the 75 cylinder head, whereby the plate may be moved longitudinally. At the rear of the plate or within the wall of the cylinder is a passage 22 extending from a point intermediate the ends of the cylinder to the passage in the cylinder head, which latter passage delivers 80 directly into the cylinder. The plate 20 is provided with an aperture or port 23, whereby the compressed gases within the piston may escape through the exhaust port 7 and port 23 to the passage 22 and thence to the explosion chamber. A baffle-plate 24 is provided 85 within the explosion chamber for directing the incoming charge across the end of the cylinder, and within the space in the end is the igniter 25. This igniter is preferably sponge platinum in the form of a wire, but it is evident that any other catalytic substance may 90 be employed which will be heated to incandescence from the passage of the explosive mixture and serve to ignite the latter. A screen 26 of wire gauze covers the outlet from the passage 22 to the explosive chamber whereby the flame cannot travel back through the 95 passage 22. The plate 20 may be held within the wall of the cylinder in any suitable manner whereby it does not interfere in any way with the movement of the piston, but preferably the inner end of the plate is provided with three fingers 27, each of which fits 100 within a dovetail groove in the cylinder wall, and thus more effectively prevents the displacement of the lower end of the plate. The piston is provided with the usual packing rings, which may be of any suitable character, and the usual outlet or exhaust pipe 28 is 105 provided in the cylinder wall intermediate the ends and in a position to be uncovered by the piston when the latter is at the end of its power stroke.

In the operation of my improved engine the pipe 18 is in communication with the carburetor, or other suitable source of explosive mixture, and the pipe 28 communicates with the outside atmosphere or with the muffler. In Fig. 1 the piston is represented in the position it would occupy immediately after the explosion has taken place in the space above the piston, and upon its outward movement the valve 19 would close, and the gas in the cylinder below the piston would be forced through the port 6 and past the valve 8 into the space 5 within the piston. At the end of the outward stroke the exhaust port 28 will be uncovered and the main portion of the exhaust gas would rush out from the explosion chamber. As the piston starts on the inward stroke, due to the action of the fly-wheel, the valve 8 closes to prevent the escape of the compressed gas from the space within the piston, the valve 19 opens to admit more of the explosive charge to the space below the piston, and the wrist-pin 13 is brought to the position shown in Fig. 3, whereby the explosion chamber may still communicate with the outside atmosphere through the piston rod and wrist-pin. As the port 7 of the piston passes the port 23 of the plate 20, a highly compressed charge within the piston rushes out into the passage 22 and into the explosion chamber above the piston. By this time the further turning of the wrist-pin 13 closes the outlet through the piston rod and the rush of gas past the igniter 25, causes the sudden rise in temperature thereof and results in the ignition 30 and explosion of the charge, whereupon the above series of steps is repeated.

The plate 20 having the port 23 is freely movable within the wall of the cylinder and may be adjusted to any desired position. The position occupied by the plate 20 determines the time at which the explosive charge will enter the explosion chamber and thus indirectly determines the time at which the explosion will take place. By enlarging or reducing the size of the port 23, the amount of the explosive charge which it is desired to admit to the cylinder, may be readily controlled. Thus, the plate 20, in controlling both the amount of the explosive charge and the time at which it is admitted, serves as a speed regulator, obviating the necessity of the employment of any other regulator of any kind. By placing the explosion chamber in communication with the outside atmosphere for a brief period after the main exhaust port has been closed, the last traces of the exhaust gas may be permitted to escape. The time at which the passage 50 through the piston rod will be opened and closed may be readily controlled by means of the adjustment of the wrist-pin 13 within the connecting rod 14, which adjustment may be readily secured by means of set screws or in any other suitable manner.

By controlling the time of the admission of the explosive charge, no electricity is needed and the complicated sparkler usually employed is entirely done away with. The catalytic agent, preferably platinum, is always ready for use and never needs any attention 60 or repairing of any kind. The only valves in the entire engine are the two check valves controlling the inlet to the cylinder and the inlet to the hollow piston, and as these are very simple in their operation, it is evident that there is very little liability of any of the parts of 65 the engine getting out of order or requiring attention.

venting of the cylinder is much more complete than in any two-cycle engine heretofore known, by reason of the double exhaust means and the baffle plate 24, adjacent the inlet end of the passage 22.

Having thus described my invention I claim as new, 70 and desire to secure by Letters Patent:

1. An internal combustion engine, comprising a cylinder provided with an inlet port in the wall thereof, a piston within said cylinder and adapted to control said port, and means for adjusting said port longitudinally of the 75 cylinder.

2. An internal combustion engine, comprising a cylinder having an explosion chamber at one end and a compression chamber at the other end, and provided with a passage having ports communicating with the compression chamber and explosion chamber, a piston within said cylinder and adapted to control one of said ports, and means for adjusting said port longitudinally of the cylinder. 80

3. An internal combustion engine, comprising a cylinder having an explosion chamber at one end and a compression chamber at the other end, said cylinder being provided with a passage establishing communication between the compression chamber and the explosion chamber, and means for adjusting the point of communication between the passage and the compression chamber longitudinally 85 of the cylinder. 90

4. An internal combustion engine comprising a cylinder having an explosion chamber at one end and a compression chamber at the opposite end, means for admitting the charge to the compression chamber, a hollow piston within 95 said cylinder and having a valve-controlled port communicating with said compression end of the cylinder, a port in the wall of the piston whereby the compressed charge may escape to the explosion end of the cylinder, and means for adjusting the outlet from said port longitudinally of 100 the cylinder.

5. An internal combustion engine comprising a cylinder having a plate embedded in the wall thereof and longitudinally adjustable, and a hollow piston having a port adjacent said plate, the wall of the cylinder being provided with a passage and the plate being provided with a port whereby the explosive charge may pass from the hollow piston to the explosion end of the cylinder, and whereby the time of such admission may be controlled by the longitudinal adjustment of the plate. 110

6. An internal combustion engine comprising a cylinder having a passage in the wall thereof and communicating with the explosion end of the cylinder, an adjustable plate controlling the inlet end of said passage and provided with a port, a piston having a port adapted to communicate with the port in the plate, whereby the time of admission of the charge to the explosion end of the cylinder may be controlled, and a catalytic agent serving as an igniter and located in the path of the incoming gas. 115

7. An internal combustion engine having a cylinder, a cylinder head provided with a recess therein and an inlet port, a baffle plate adjacent said cylinder head, and a catalytic substance within said recess and serving to ignite the explosive charge as it passes between the baffle plate and the cylinder head. 120

8. An internal combustion engine having a cylinder, a cylinder head provided with a recess therein and an inlet port adjacent said recess, a baffle plate adjacent said cylinder head and lying substantially parallel thereto, an igniter within said recess and serving to ignite the explosive charge as it passes between the baffle plate and the cylinder head, and means adjacent the inlet port for preventing the ignition of the gases in the inlet passage. 125

9. An internal combustion engine, comprising a cylinder having an explosion chamber at one end and a compression chamber at the opposite end, a passage having ports communicating with said chambers and an outlet port intermediate the ends of the cylinder, a piston within said cylinder and adapted to control one of the ports of said passage and the outlet port, and means for adjusting the position of one of said ports longitudinally of the cylinder. 135

10. An internal combustion engine comprising a cylinder

having an exhaust port intermediate its ends, a piston, a hollow piston rod adapted to serve as an auxiliary exhaust means, and means at the outer end of said piston for controlling said passage.

5 11. An internal combustion engine comprising a cylinder, a piston located therein, a piston rod having a passage extending throughout its length, and a pin rotatably mounted in the outer end of the piston rod, said pin being provided with a passage adapted to communicate with the

passage in the piston during a portion of the exhaust 10 stroke.

In testimony whereof I have signed my name to this specification in the presence of two subscribing witnesses.

Corrections in Letters Patent No. 864,086.

It is hereby certified that in Letters Patent No. 864,086, granted August 20, 1907, upon the application of Heinrich Albert Walter Drechsler, of Männedorf, Switzerland, for an improvement in "Internal-Combustion Engines," errors appear in the printed specification requiring correction, as follows: On page 2, line 66, the word "The" should be inserted at the beginning of the line, and in same line, the word "venging" should read *scavenging*; and that the said Letters Patent should be read with these corrections therein that the same may conform to the record of the case in the Patent Office.

Signed and sealed this 15th day of October, A. D., 1907.
